(57) **CLAIM**

The ornamental design for a connector terminal, as shown and described.

DESCRIPTION

FIG. 1 is a front perspective view of a connector terminal showing my new design;

FIG. 2 is a top view thereof;

FIG. 3 is a bottom view thereof;

FIG. 4 is a right side view thereof;

FIG. 5 is a left side view thereof;

FIG. 6 is a front view thereof; and,

FIG. 7 is a rear view thereof.

The broken lines depicting the remainder of the connector terminal show features that form no part of the claimed design. The uneven-length broken lines immediately adjacent to the shaded area define the bounds of the claimed design and form no part thereof.
